TRIGGER-MECHANISM FOR FIREARMS

William C. Roemer, New Haven, Conn., assignor
to Western Cartridge Company, New Haven,
Conn., a corporation of Delaware

Application December 19, 1939, Serial No. 310,011

4 Claims. (Cl. 42—69)

This invention relates to improvements in trigger-mechanisms for firearms and more particularly to trigger-mechanisms for that type of firearm wherein the breech-bolt is moved rearwardly by an action-slide or the like for the ejection of a fired cartridge and the insertion of a fresh cartridge into the cartridge-chamber of the firearm.

One of the objects of the present invention is to provide a firearm having a superior construction and arrangement of parts whereby the trigger is automatically uncoupled from the sear immediately upon the breech-bolt being unlocked and prior to the cocking of the firing-mechanism, the said trigger remaining uncoupled from the sear during the rearward and forward travel of the breech-bolt until the latter has reached its breech-closing position.

Another object of the present invention is to provide a superior trigger-mechanism having coupling-means interposed between the trigger and the sear, the said coupling-means being constructed and arranged to permit the sear to be moved into its cocking position immediately following the discharge of the firearm.

A further object of the present invention is to provide a superior trigger-mechanism having means constructed and arranged to disconnect the trigger from the sear to permit the sear to be moved into its cocking position even in the event of the trigger being held in its rearmost or firing position, so that the firearm cannot be discharged again, save upon the release and subsequent actuation of the trigger for each shot.

A still further object of the present invention is to provide a superior trigger-mechanism of compact and rugged construction for assembly in a limited space in the firearm structure and which may be assembled as a unitary structure before being installed in the firearm.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken view mainly in side elevation and partly in vertical central-longitudinal section of a firearm embodying the present invention, the breech-bolt being shown in its closed position;

Fig. 2 is an enlarged view partly in vertical

central-longitudinal section and partly in side elevation of the portions of the firearm at and adjacent the trigger-mechanism, the hammer being shown in its cocked position preparatory to the discharge of the firearm;

Fig. 3 is a view similar to Fig. 2 but showing the parts in the positions which they assume when the breech-bolt has been moved rearwardly into its retired position, cocking the firearm, and with the trigger held back in its rearmost or firing position;

Fig. 4 is a fragmentary transverse sectional view taken on the line 4—4 of Fig. 2;

Fig. 5 is a horizontal sectional view taken on the line 5—5 of Fig. 2;

Fig. 6 is a transverse sectional view taken on the line 6—6 of Fig. 2;

Fig. 7 is a similar view taken on the line 7—7 of Fig. 2;

Fig. 8 is a transverse sectional view taken on the line 8—8 of Fig. 2;

Fig. 9 is a perspective view of the trigger-unit with a portion of the trigger broken away and the sear-actuator shown in position to actuate the sear;

Fig. 10 is a perspective view of the trigger detached;

Fig. 11 is a perspective view of the sear;

Fig. 12 is a perspective view of the sear-actuator;

Fig. 13 is a broken perspective view of the rear portion of the action-slide looking mainly at the underside thereof; and

Fig. 14 is a perspective view of the hammer.

The firearm herein chosen for illustrating the present invention includes a receiver 20, a barrel 21, a receiver-extension 22, a trigger-plate 23 and a stock 24. The barrel 21 is secured to the said receiver 20 and extends forwardly therefrom in the usual manner of firearms, and the receiver-extension 22 extends rearwardly from the said receiver and serves to couple the latter firmly to the stock 24. The trigger-plate 23 is secured to the underside of the receiver 20 in any suitable manner, and has an action-slide 25 resting upon its upper face with capacity for reciprocating movement longitudinally of the firearm.

The action-slide 25 may be moved rearwardly in any suitable manner such, for instance, as by a gas-operated piston as is shown in my co-pending application, Serial No. 313,650 filed January 13, 1940. The said action-slide includes parallel spaced-apart side-arms 26—27 held in laterally-spaced relationship at their rear ends by a cross-head 28 to the respective opposite sides of which

the rear ends of the side-arms 26 and 27 are welded, brazed or otherwise secured.

The receiver 20 includes a top wall 29a from the respective opposite sides of which depend two laterally-spaced-apart side walls 29-29 providing a breech-bolt-receiving chamber 30 in which a breech-bolt 31 is adapted to be tilted and reciprocated by the action-slide 25. The reciprocating breech-bolt 31 has pivotally coupled to its rear end, by means of a pivot-pin 32, the 10 upper end of an operating-link 33 which latter is also pivotally secured at its lower end by a pivot-pin 34 to the cross-head 28 of the action-slide 25.

Extending rearwardly from and formed integral with the cross-head 28 of the action-slide 25 is a stem 35 bearing at its rear end against the forward end of a spring-plunger mounted with capacity for reciprocating movement in the receiver-extension 22 before referred to, and 20 which is constantly urged forwardly by a breech-bolt-return spring 36 (Fig. 1).

The trigger-plate 23 is formed with a longitudinal clearance-groove 37 resulting in the formation of laterally-spaced-apart side walls 25 38-38 from the respective upper edges of which ears 39-39 respectively project upwardly and serve to mount the respective opposite ends of a pivot-pin 40 pivotally mounting a hammer 41 between the said ears 39-39. It may here be 30 stated that the side-arms 26 and 27 of the action-slide 25 are mounted for reciprocatory movement between the upper edges of the side walls 38-38 of the trigger-plate 23 and the lower edges of the side walls 29-29 of the receiver 15.

The hammer 41 is formed with a longitudinal clearance-passage 42 in which extends the forward end of a spring-plunger 43 pivotally secured by a pivot-pin 44 to the said hammer 41. The spring-plunger 43 is provided with a spring-guiding stem 45 mounted for sliding movement in a transversely-extending abutment-member 46 pivotally mounted at its respective opposite ends in the side walls 38-38 of the trigger-plate 23. Interposed between the forward face of the abutment-member 46 and a shoulder 47 formed on the spring-plunger 43 is a helical hammer-spring 48 encircling the forward portion of the stem 45. The opposite ends of the said hammer-spring 48 respectively thrust against the forward face of the abutment-member 46 and the shoulder 47 of the plunger 43 to constantly urge the hammer 41 forwardly to strike a firing-plunger 49 carried by the breech-bolt 31 for the discharge of a cartridge. It may here be noted that the rear portion of the action-slide 25 is provided with a longitudinal clearance-slot 50 formed partly in the stem 35 and partly in the cross-head 28 thereof. The hammer 41 is located in the said clearance-slot 50 when in its cocked position and the 55 said hammer and the forward portion of the spring-plunger 43 are adapted to move through the said slot under the urge of the hammer-spring 48 to effect the discharge of the firearm.

The trigger-plate 23 carries a trigger 51 mainly located in the clearance-groove 37 thereof and which is mounted for pivotal movement upon a pivot-pin 52 extending transversely of the said trigger-plate with its respective opposite ends supported in the side walls 38-38 of the said trigger-plate 23, as is shown in Fig. 6. The trigger 51 has its major portion located in the clearance-groove 37 of the trigger-plate 23 and is formed with a finger-piece 53 extending downwardly through a vertical clearance-slot 54

formed in the trigger-plate 23 and leading downwardly from the clearance-groove 37 therein to the under face of the said trigger-plate. The said finger-piece 53 is enclosed by the usual loop-like trigger-guard 55.

The trigger 51 is formed with two laterally-spaced-apart forwardly-extending parallel substantially-L-shaped arms 56-56 between the forward or outer portions of which extends an integral bridge 57, for the purpose as will hereinafter appear. The central portion of the said trigger 51 is formed with a longitudinal clearance-groove 58 receiving the rear end of a sear 59 mounted for independent pivotal movement, with respect to the trigger 51, upon the pivot-pin 52 before referred to, and which also pivotally mounts the said trigger.

The sear 59 extends forwardly between the arms 56-56 of the trigger 51 and is formed on its upper edge and about midway of its length with a forwardly-facing cocking-shoulder 60 adapted to engage a rearwardly-facing cocking-abutment 61 forming one face of a cocking-notch 62 provided in the hammer 41. The sear 59, by the engagement of its cocking-shoulder 60 with the cocking-abutment 61 of the hammer 41, serves to releasably maintain the said hammer in its cocked position against the tension of the hammer-spring 48 until such time as the cocking-shoulder 60 is moved downwardly out of engagement with the cocking-abutment 61 of the hammer 41, by the actuation of the trigger 51, all as will more clearly hereinafter appear.

Intermediate the pivot-pin 52 and the cocking-shoulder 60, the sear 59 is provided with a downwardly-opening spring-socket 63 in which is located a helical sear-spring 64 having its lower end seated against the adjacent bottom of the clearance-groove 37 in the trigger-plate 23 as is clearly shown in Figs. 2 and 3. The sear-spring 64 exerts a constant but yielding effort to move the sear 59 upwardly into position to interpose its cocking-shoulder 60 in the path of movement of the cocking-abutment 61 of the hammer 41. At its upper forward corner, the sear 59 is notched to form an upwardly-facing abutment 65 and a forwardly-facing limiting-shoulder 66 for the purpose as will hereinafter appear.

For the purpose of coupling the trigger 51 to the sears 59 and uncoupling the same therefrom, the said trigger carries an L-shaped sear-actuator 67 pivotally mounted between the outer ends of the L-shaped arms 56-56 of the said trigger 51. The sear-actuator 67 is pivotally mounted for rocking movement relative to the trigger 51, upon a pivot-pin 68 having its opposite ends respectively mounted in the arms 56-56 of the trigger 51, as shown particularly well in Figs. 8 and 9. The sear-actuator 67 normally has the lower face of its depending arm 69 located immediately over the upwardly-facing abutment 65 of the sear 59 with its rear edge in engagement with the limiting-shoulder 66 of the said sear. At its rear or outer end, the substantially-horizontal arm 70 of the sear-actuator 67 mounts a relatively-long cam-pin 71 extending transversely through the said arm 70 with each of its respective opposite ends normally disposed in the adjacent one of two clearance-notches 72-72 respectively formed in the under edge of the adjacent rear portion of the side-arms 26 and 27 of the action-slide 25 when the latter is in its forward position.

Intermediate the pivot-pin 68 and the cam-pin 71, the horizontal arm 70 of the sear-actuator

67 is provided with a downwardly-opening spring-socket 73 housing a spring-plunger 74 formed with a stem 75 extending upwardly through the end wall of the said spring-socket. Encircling the stem 75 of the spring-plunger 74 and housed within the spring-socket 73 is a helical spring 76 thrusting at one end against the end wall of the said spring-socket and at the other end against the upper face of the spring-plunger 74 to constantly urge the said spring-plunger into seated engagement with the upper face of the bridge 57 forming part of the trigger 51 as before described.

The spring 76 just above referred to, thus constantly urges the sear-actuator 67 to turn in a clockwise direction as viewed in Figs. 2 and 3 to maintain the rear face of the lower end of the vertical arm 69 of the said sear-actuator in engagement with the limiting-abutment 66 of the sear 59 and in position to engage the abutment 65 thereof for the purpose as will hereinafter appear. The spring 76 also serves to urge the opposite ends of the cam-pin 71 respectively upwardly into the clearance-notches 72-72 of the action-slide 25 for engagement by forwardly- and downwardly-inclined uncoupling-cams 77-77 each of which forms the forward wall of one of the clearance-notches 72-72. The uncoupling-cams 77-77 are adapted to engage the adjacent opposite ends of the cam-pin 71 when the action-slide 25 is moved rearwardly to rock the sear-actuator 67 in a counterclockwise direction from the position in which it is shown in Fig. 2 into that shown in Fig. 3. This counterclockwise turning of the sear-actuator 67 will serve to swing the vertical-arm 69 thereof out of the path of movement of the abutment 65 of the sear 59. The described counterclockwise turning movement of the sear-actuator 67 will be effected against the tension of the spring 76 which holds the respective opposite ends of the cam-pin 71 in engagement with the lower edges of the adjacent side-arms 26 and 27 of the action-slide 25 during the major part of its rearward and forward travel. The retention of the cam-pin 71 as just described, prevents the said sear-actuator 67 from turning clockwise until the action-slide 25 has reached its forward position and the clearance-notches 72-72 of the said action-slide are again in registration with the opposite ends of the cam-pin 71.

To hold the trigger 51 in its normal position the said trigger is formed adjacent its finger-piece 53 with an upwardly-and-rearwardly-inclined spring-socket 78 opening through the rear upper edge thereof and housing a spring-plunger 79 having a guide-stem 80 encircled by a helical trigger-spring 81. One end of the spring 81 thrusts against the bottom of the spring-socket 78 while the opposite end thrusts against the adjacent face of the spring-plunger 79 to thus hold the said spring-plunger 79 in seated engagement with the adjacent portion of the trigger-plate 23 and the trigger 51 in its normal or non-firing position.

For the purpose of description let it be assumed that the cartridge-chamber of the firearm contains a cartridge and that the hammer 41 is cocked and the associated parts are in position in readiness for the discharge of the firearm, as shown in Figs. 1 and 2. Under this condition the breech-bolt 31 is in its breech-closing position and the action-slide 25 is in its forward position.

If rearward draft is now applied to the finger- 75

piece 53 of the trigger 51 to rock the said trigger clockwise about its pivot-pin 52 against the tension of the trigger-spring 81, the forward ends of the L-shaped arms 56-56 of the said trigger 51 will be swung downwardly. This downward movement of the forward ends of the said arms 56-56 of the trigger 51 will correspondingly bodily move the sear-actuator 67 carried thereby downwardly. Owing to the position of the end 10 of the arm 69 of the sear-actuator 67 over the upwardly-facing abutment 65 of the sear 59, it will be readily apparent that any downward movement of the said sear-actuator will cause the outer end of the sear 59 to be concurrently moved downwardly to thus withdraw the cocking-shoulder 60 thereof from its engagement with the cocking-abutment 61 of the hammer 41. The withdrawal of the cocking-shoulder 60 as just described will enable the said hammer 41 to be rapidly swung in a clockwise direction as viewed in Fig. 2, under the urge of the hammer-spring 48. The hammer 41, near the completion of its clockwise turning movement under the urge of the hammer-spring 48, will sharply strike the 15 rear exposed end of the firing-plunger 49 to snap the latter forwardly to discharge the cartridge contained in the cartridge-chamber of the firearm in a manner well understood in the art.

20 It will be apparent from the foregoing that rearward draft upon the trigger 51 will cause the said trigger, together with the sear-actuator 67 carried thereby and the sear 69 organized therewith, to be simultaneously rocked in a clockwise direction to effect the withdrawal of the cocking-shoulder 60 of the sear 59 from its engagement with the cocking-abutment 61 of the hammer 41, since the parts 51, 59 and 67 in effect form a unitary structure.

25 The downward movement of the forward end of the trigger 51, together with the sear-actuator 67, as above described, will have correspondingly moved the cam-pin 71 carried by the said sear-actuator. The downward movement of the cam-pin 71 is, however, only part way of its full downward movement and is insufficient to withdraw the opposite ends of the said cam-pin from their complementary clearance-notches 72-72 in the action-slide 25. The opposite ends of the said cam-pin 71 will thus remain partly in the said clearance-notches 72-72 of the action-slide 25 for the purpose as will hereinafter be described.

30 Following the discharge of the firearm the rearward movement of the action-slide 25 will effect the unlocking and rearward movement of the tilting and reciprocating breech-bolt 31 to cause the ejection of the just fired cartridge. This rearward travel or movement of the action-slide 25 will cause the uncoupling-cams 35 77-77 of the said action-slide 25 to respectively engage the respective opposite ends of the cam-pin 71 located in their respective clearance-notches 72-72 immediately upon the start of the rearward travel of the said action-slide 25. The uncoupling-cams 77-77, upon engaging the respective opposite ends of the cam-pin 71, will cam the latter downwardly to thus swing the sear-actuator 67 in a counterclockwise direction against the tension of the helical spring 76 carried thereby.

35 The counterclockwise movement as above described will swing the lower end of the arm 69 of the sear-actuator 67 forwardly to thus remove the same from its engagement with the abutment

65 thus releasing the sear 59 from the restraint against upward movement imposed thereon by the said sear-actuator 67. The uncoupling or disconnection of the sear-actuator 67 from the sear 59 will permit the sear-spring 64 to assert itself to swing the sear 59 upwardly to enable its cocking-shoulder 60 to be re-engaged by the cocking-abutment 61 of the hammer 41 when the said hammer is swung into its cocked position by the rearward movement of the action-slide 25.

It may here be noted that the action-slide 25 has a portion 82 of its cross-head 28 which is adapted to engage the forward face of the hammer 41 during the rearward travel of the said action-slide to swing the hammer 41 in a 15 counterclockwise direction against the tension of its hammer-spring 43. It will also be understood that the respective opposite ends of the cam-pin 71 of the sear-actuator 67 are in engagement with the respective lower edges of the side-arms 26 and 27 of the action-slide 25 during all but the initial rearward travel of the said action-slide. This engagement temporarily prevents the sear-actuator 67 from again assuming the position in which it is shown in Fig. 2 under the urge of the spring 76, and serves to hold the lower end of the arm 69 of the said sear-actuator 67 out of the path of movement of the abutment 65 of the sear 59 until such time as the clearance-notches 72-72 of the action-slide 25 are again respectively in registration with the opposite ends of the cam-pin 71 by the full return movement of the said action-slide.

By preventing the arm 69 of the sear-actuator 67 from re-engaging with the abutment 65 of the sear 59 until such time as the action-slide 25 is returned fully to its forward position under the urge of the breech-bolt-closing spring 36, the sear 59 is rendered immune, during this time interval, against being again swung downwardly by any movement of the trigger 51.

From the foregoing, considered in conjunction with the accompanying drawings, it will be apparent that substantially immediately following the initiation of the rearward movement of the action-slide 25 the sear-actuator 67 is so moved as to be rendered inoperative until such time as not only has the said action-slide been returned to its full forward position but rearward draft upon the trigger 51 has been relaxed. In this manner the sear 59 is freed of restraint against upward movement immediately following the discharge of the firearm so that it may be in position to hold the hammer 41 in its cocked position. Furthermore, the repeated discharge of the firearm is prevented until such time as the operator of the firearm has relaxed rearward draft upon the trigger 51, and the action-slide 25 as well as the breech-bolt 31 have been returned to their full forward position.

In the event that it is desired to retire the breech-bolt 31 to effect the removal of an unfired cartridge from the firearm this may be effected by rearwardly moving the action-slide 25 without regard to the trigger 51. During this operation, however, the sear-actuator 67 will be swung in a counterclockwise direction to thereby effectively disconnect the trigger 51 from the sear 59 to thus guard against the release of the hammer 41 during this operation.

By organizing the trigger, sear and sear-actuator in a manner such as is herein shown and described, it becomes feasible to conveniently assemble the three said elements and adjust the

same to each other prior to their being installed in the firearm structure. Furthermore, by the construction and arrangement referred to, the firing-control mechanism is rendered compact, durable and reliable in its operation.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A firearm-structure including in combination: a pivotal hammer; pivot-means for the said pivotal hammer; a pivotal trigger pivoted to the firearm-structure at a point rearwardly of the pivot-means of the said pivotal hammer and having an arm extending forwardly beyond the pivot-means of the said pivotal hammer; a pivotal sear also pivoted to the firearm-structure at a point to the rear of the pivot-means of the said pivotal hammer and having an arm extending forwardly of the said pivot-means, the said pivotal sear having a portion engageable with the said pivotal hammer to releasably hold the same in its cocked position; an L-shaped sear-actuator carried by and pivoted to the said trigger at a point forwardly of the pivot-means of the said pivotal hammer and having a rearwardly-extending arm and a downwardly-extending arm extending into releasable engagement with the forwardly-extending arm of the said sear; spring-means yieldingly urging the said L-shaped sear-actuator to turn in a direction required to swing its downwardly-extending arm rearwardly for engagement with the arm of the said pivotal sear; and releasing-means movable substantially longitudinally of the firearm-structure and engaging with a portion of the rearwardly-extending arm of the said sear-actuator to positively turn the same in a direction to depress the said rearwardly-extending arm and to swing the said downwardly-extending arm of the said sear-actuator forwardly out of coacting engagement with the forwardly-extending arm of the said pivotal sear.

2. A firearm-structure including in combination: a pivotal hammer; pivot-means for the said pivotal hammer; a pivotal trigger pivoted to the firearm-structure at a point rearwardly of the pivot-means of the said pivotal hammer and having an arm extending forwardly beyond the pivot-means of the said pivotal hammer; a pivotal sear also pivoted to the firearm-structure at a point coaxial with the said pivotal trigger and to the rear of the pivot-means of the said pivotal hammer and having an arm extending forwardly of the said pivot-means, the said pivotal sear having a portion engageable with the said pivotal hammer to releasably hold the same in its cocked position; an L-shaped sear-actuator carried by and pivoted to the said trigger at a point forwardly of the pivot-means of the said pivotal hammer and having a rearwardly-extending arm and a downwardly-extending arm extending into releasable engagement with the forwardly-extending arm of the said sear; spring-means yieldingly urging the said L-shaped sear-actuator to turn in a direction required to swing its downwardly-extending arm rearwardly for engagement with the arm of the said pivotal sear; and releasing-means movable

substantially longitudinally of the firearm-structure and engaging with a portion of the rearwardly-extending arm of the said sear-actuator to positively turn the same in a direction to depress the said rearwardly-extending arm and to swing the said downwardly-extending arm of the said sear-actuator forwardly out of coacting engagement with the forwardly-extending arm of the said pivotal sear.

3. A firearm-structure including in combination: a pivotal hammer; pivot-means for the said pivotal hammer; a pivotal trigger pivoted to the firearm-structure at a point rearwardly of the pivot-means of the said pivotal hammer and having an arm extending forwardly beyond the pivot-means of the said pivotal hammer and provided with a substantially-horizontal sear-receiving recess; a pivotal sear also pivoted to the firearm-structure at a point to the rear of the pivot-means of the said pivotal hammer and having an arm extending forwardly of the said pivot-means and through the sear-receiving recess in the forwardly-extending arm of the said trigger, the said pivotal sear having a portion engageable with the said pivotal hammer to releasably hold the same in its cocked position; an L-shaped sear-actuator carried by and pivoted to the said trigger at a point forwardly of the pivot-means of the said pivotal hammer and having a rearwardly-extending arm and a downwardly-extending arm extending into releasable engagement with the forwardly-extending arm of the said sear; spring-means yieldingly urging the said L-shaped sear-actuator to turn in a direction required to swing its downwardly-extending arm rearwardly for engagement with the arm of the said pivotal sear; and releasing-means movable substantially longitudinally of the firearm-structure and engaging with a portion of the rearwardly-extending arm of the said sear-actuator to positively turn the same in a direction to depress the said rearwardly-extending arm and to swing the said downwardly-extending arm of the

said sear-actuator forwardly out of coacting engagement with the forwardly-extending arm of the said pivotal sear.

4. A firearm-structure including in combination: a pivotal hammer; pivot-means for the said pivotal hammer; a pivotal trigger pivoted to the firearm-structure at a point rearwardly of the pivot-means of the said pivotal hammer and having an arm extending forwardly beyond the pivot-means of the said pivotal hammer and provided with a substantially-horizontal sear-receiving recess; a pivotal sear also pivoted to the firearm-structure at a point coaxial with the said pivotal trigger and to the rear of the pivot-means of the said pivotal hammer and having an arm extending forwardly of the said pivot-means and through the sear-receiving recess in the forwardly-extending arm of the said trigger, the said pivotal sear having a portion engageable with the said pivotal hammer to releasably hold the same in its cocked position; an L-shaped sear-actuator carried by and pivoted to the said trigger at a point forwardly of the pivot-means of the said pivotal hammer and having a rearwardly-extending arm and a downwardly-extending arm extending into releasable engagement with the forwardly-extending arm of the said sear; spring-means yieldingly urging the said L-shaped sear-actuator to turn in a direction required to swing its downwardly-extending arm rearwardly for engagement with the arm of the said pivotal sear; and releasing-means movable substantially longitudinally of the firearm-structure and engaging with a portion of the rearwardly-extending arm of the said sear-actuator to positively turn the same in a direction to depress the said rearwardly-extending arm and to swing the said downwardly-extending arm of the said sear-actuator forwardly out of coacting engagement with the forwardly-extending arm of the said pivotal sear.

WILLIAM C. ROEMER.
